(57) **ABSTRACT**

Prior to increasing the voltage level of an input signal to be sampled in a step-by-step manner and writing a signal voltage V_{sig} at a desired voltage level, a precharge is performed which writes a precharge voltage V_{pre} , lower than the signal voltage V_{sig} , so as to apply the same voltage V_{pre} to the gate of a drive transistor in advance. This not only provides a reduced gate-to-source voltage of the drive transistor at the time of writing of the signal voltage V_{sig} but also extends a mobility correction time required for a mobility correction operation. The extension of the mobility correction time required for the mobility correction operation ensures a relatively smaller variation in the correction time, thus suppressing the variation in brightness. The extension also permits a write pulse to be set to the optimal pulse width.

**DISPLAY APPARATUS, DRIVING METHOD
OF DISPLAY APPARATUS AND ELECTRONIC
EQUIPMENT**

TECHNICAL FIELD

The present invention relates to a display apparatus, a driving method of the display apparatus and electronic equipment. The present invention relates particularly to a flat panel display apparatus having pixels including light-emitting elements arranged in a matrix form, a driving method of the display apparatus and electronic equipment having the display apparatus.

BACKGROUND ART

In the field of image display apparatuses, recent years have seen the development and commercialization of flat panel display apparatuses having pixels (pixel circuits) including light-emitting elements arranged in a matrix form. Among such display apparatuses are organic EL display apparatuses using organic EL (electro luminescence) elements as the light-emitting elements of the pixels. The organic EL element is an example of so-called current-driven light-emitting elements whose emission brightness changes with change in current flowing through the element. The organic EL element relies on the phenomenon that the organic thin film thereof emits light when an electric field is applied thereto.

Such organic EL display apparatuses offer low power consumption thanks to their organic EL elements which can be driven by an applied voltage of 10 V or less. Further, organic EL elements are self-luminous. This makes organic EL display apparatuses more advantageous than liquid crystal display apparatuses designed to display an image by controlling the light intensity from the light source (backlight) for each pixel including a liquid crystal cell using the cell. Such advantages include high image visibility and ease of reduction in weight and thickness thanks to no need for illuminating members such as backlight which are necessary for liquid crystal display apparatuses. Further, organic EL elements offer extremely high response speed or approximately several μ seconds. As a result, organic EL display apparatuses produce no afterimage during display of a moving image.

As with liquid crystal display apparatuses, organic EL display apparatuses can be driven by passive or active matrix. It should be noted, however, that although passive matrix display apparatuses are simple in structure, they have disadvantages including difficulties in implementing a large-size, high-definition display apparatus. Therefore, the development of active matrix display apparatuses has been brisk in recent years. In such display apparatuses, the current flowing through the light-emitting element is controlled by an active element provided together with the light-emitting element in the same pixel circuit such as insulated gate electric field effect transistor (generally TFT (Thin Film Transistor)).

Incidentally, the I-V characteristic (current vs voltage characteristic) of organic EL elements is generally known to deteriorate with time (so-called secular deterioration). In a pixel circuit using an N-channel TFT as a transistor adapted to drive an organic EL element (hereinafter described as "drive transistor") by a current, the organic EL element is connected to the source of the drive transistor. Therefore, secular deterioration of the I-V characteristic of the organic EL element leads to a change in a gate-to-source voltage V_{GS} of the drive transistor, thus changing the emission brightness of the organic EL element.

A more detailed description thereof will be given below. The source potential of a drive transistor is determined by the operating point of the drive transistor and the organic EL element. In the event of a deterioration of the I-V characteristic of the organic EL element, the operating point of the drive transistor and the organic EL element changes. This leads to a change in the source potential of the drive transistor even if the same potential is applied to the gate of the drive transistor. As a result, the gate-to-source voltage V_{GS} of the drive transistor changes, changing the current flowing through the drive transistor. This changes the current flowing through the organic EL element, changing the emission brightness of the organic EL element.

With a pixel circuit using a polysilicon TFT, on the other hand, a threshold voltage V_{TH} of the drive transistor and a mobility μ of the semiconductor thin film making up the channel of the drive transistor change with time in addition to the secular deterioration of the I-V characteristic of the organic EL element. Moreover, the threshold voltage V_{TH} and the mobility μ may be different between different pixels due to a manufacturing process variation (that is, different transistors exhibit different characteristics).

In the event of a difference in the threshold voltage V_{TH} of the drive transistor or the mobility μ , the current flowing through the drive transistor changes. This leads to a change in emission brightness of the organic EL element between different pixels even if the same voltage is applied to the gate of the drive transistor, thus impairing the uniformity over the screen.

For this reason, each of the pixel circuits has various compensation and correction functions to ensure that the emission brightness of the organic EL element remains constant even in the event of a secular deterioration of the I-V characteristic of the organic EL element or a secular change in the threshold voltage V_{TH} or the mobility μ of the drive transistor without being affected by such a change or deterioration. One of the functions is the compensation function adapted to compensate for the change in characteristic of the organic EL element. Another function is the correction function adapted to correct the change in the threshold voltage V_{TH} of the drive transistor (hereinafter written as "threshold correction"). Still another function is the correction function adapted to correct the mobility μ of the drive transistor (hereinafter written as "mobility correction") (refer, for example, to Japanese Patent Laid-Open No. 2006-133542).

DISCLOSURE OF INVENTION

In the prior art described in Japanese Patent Laid-Open No. 2006-133542, each pixel circuit has the compensation function adapted to compensate for the change in characteristic of the organic EL element and the correction functions adapted to correct the change in the threshold voltage V_{TH} and the mobility μ of the drive transistor. As a result, the emission brightness of the organic EL element remains constant in the event of a secular deterioration of the I-V characteristic of the organic EL element or a secular change in the threshold voltage V_{TH} or the mobility μ of the drive transistor without being affected by such a change or deterioration. However, each pixel circuit includes a large number of elements, thus posing a hurdle for the reduction of the pixel size.

A possible solution to reducing the number of elements and interconnections making up the pixel circuit would be to ensure that a supply potential supplied to the drive transistor of the pixel circuit can be changed. In this manner, the drive transistor would be capable of controlling the emission and non-emission periods of the organic EL element by changing

the supply potential. As a result, the transistor adapted to control the emission and non-emission periods could be omitted.

This technique makes it possible to configure a pixel circuit with the minimum required number of elements. That is, a pixel circuit can be made up of a write transistor configured to sample an input signal voltage and write the voltage to the pixel, a holding capacitance configured to hold the input signal voltage written by the write transistor, and a drive transistor configured to drive the light-emitting element based on the input signal voltage held by the holding capacitance.

As described above, if the drive transistor serves also as a transistor configured to control the emission and non-emission periods of the organic EL element in order to reduce the number of elements making up the pixel circuit, the above mobility correction is carried out simultaneously with the writing of the input signal voltage by the write transistor. Incidentally, in the prior art described in Japanese Patent Laid-Open No. 2006-133542, the mobility correction is performed after the write period of the input signal voltage is totally complete.

Here, the mobility correction operation is determined by the gate-to-source voltage V_{GS} of the drive transistor at the beginning of the correction and the operation time (mobility correction time). And, there is a relationship between the optimal mobility correction time for the mobility correction to provide the best image quality and the gate-to-source voltage V_{GS} of the drive transistor at the beginning of the correction. That is, the higher the gate-to-source voltage V_{GS} , the shorter the optimal mobility correction time.

On the other hand, the mobility correction time is determined only by the pulse width of a write pulse adapted to sample and write the input signal voltage to the pixels (pulse adapted to drive the write transistor). Therefore, even if there is a variation in pulse width of a write pulse by the same amount of time between the long and short optimal mobility correction times, the variation in pulse width of a write pulse is relatively large when the optimal mobility correction time is short. The variation in pulse width leads to variation in brightness, thus resulting in degraded image quality.

Further, when the optimal mobility correction time is short, the write pulse width can be determined only discontinuously because of the system adapted to determine this pulse width. More specifically, the write pulse width can be determined only in the unit of pulse width of the master clock based on which the system operates. As a result, it is probable that the optimal setting may not be achieved.

In light of the foregoing, it is an object of the present invention to provide a display apparatus, driving method of the display apparatus and electronic equipment using the same for providing a relatively smaller variation in mobility correction time required for a mobility correction operation by extending the mobility correction time so as to suppress the variation in brightness and permit a write pulse to be set to the optimal pulse width.

In order to achieve the above object, a display apparatus according to the present invention includes a pixel array section and write scan circuit. The pixel array section has pixels arranged in a matrix form. Each of the pixels includes a light-emitting element, write transistor, holding capacitor and drive transistor. The write transistor samples and writes an input signal voltage. The holding capacitor holds the input signal voltage written by the write transistor. The drive transistor drives the light-emitting element based on the input signal voltage held by the holding capacitor. The write scan circuit supplies a write pulse adapted to drive the write transistor to the pixels in the pixel array section on a row-by-row

basis. The pixels in the row scanned by the write scan circuit are supplied with the input signal voltage. The level of the input signal voltage is increased in a step-by-step manner.

In the display apparatus configured as described above and 5 electronic equipment using the same, there is a relationship between the optimal mobility correction time for the mobility correction to provide the best image quality and the gate-to-source voltage of the drive transistor at the beginning of the correction. That is, the higher the gate-to-source voltage V_{GS} , the shorter the optimal mobility correction time. In other 10 words, the lower the gate-to-source voltage V_{GS} , the longer the optimal mobility correction time.

Therefore, prior to increasing the voltage level of the input 15 signal to be sampled in a step-by-step manner and writing the signal voltage at a desired voltage level, a voltage lower than the signal voltage is written in advance (also referred to as the precharge). This raises the gate potential of the drive transistor, also causing the source potential to rise. As a result, the 20 gate-to-source voltage of the drive transistor at the time of writing of the input signal voltage at a desired level, i.e., at the beginning of a mobility correction period, can be kept lower than if the precharge were not performed. This provides a 25 longer optimal mobility correction time (extends the mobility correction time longer than if the precharge were not performed).

BRIEF DESCRIPTION OF DRAWINGS

30 FIG. 1 is a system configuration diagram illustrating the schematic configuration of an organic EL display apparatus according to an embodiment of the present invention;

FIG. 2 is a circuit diagram illustrating an example of specific configuration of an output portion of a horizontal drive 35 circuit;

FIG. 3 is a circuit diagram illustrating a concrete configuration example of a pixel (pixel circuit);

BEST MODE FOR CARRYING OUT THE INVENTION

The preferred embodiments of the present invention will be described in detail below with reference to the accompanying drawings.

FIG. 1 is a system configuration diagram illustrating the schematic configuration of an active matrix display apparatus according to an embodiment of the present invention. Here, a description will be given, as an example, about an active matrix organic EL display apparatus. This EL display apparatus uses organic EL elements as light-emitting elements of pixels. The organic EL element is an example of so-called current-driven light-emitting elements whose emission brightness changes with change in current flowing through the element.

As illustrated in FIG. 1, an organic EL display apparatus 10 according to the present embodiment includes a pixel array section 30 and drive sections disposed around the pixel array section 30 such as a write scan circuit 40, a power supply scan circuit 50 and a horizontal drive circuit 60. The pixel array section 30 has pixels (PXLC) 20 arranged two-dimensionally in a matrix form. The drive sections, namely, the write scan, power supply scan and horizontal drive circuits 40, 50 and 60 drive each of the pixels 20.

The pixel array section 30 has, in an m by n pixel array, scan lines 31-1 to 31-m and power supply lines 32-1 to 32-m, one each for each pixel row. The pixel array section 30 also has signal lines 33-1 to 33-n, one each for each pixel column.

The pixel array section 30 is normally formed on a transparent insulated substrate such as glass substrate and has a flat panel construction. Each of the pixels 20 of the pixel array section 30 can be formed with amorphous silicon TFT (Thin Film Transistor) or low-temperature polysilicon TFT. When low-temperature polysilicon TFT is used, the write scan circuit 40, the power supply scan circuit 50 and the horizontal drive circuit 60 can also be incorporated on the display panel (substrate) 70 on which the pixel array section 30 is formed.

The write scan circuit 40 includes a shift register or other components. To write a video signal to the pixels 20 of the pixel array section 30, the write scan circuit 40 supplies sequential scan signals WS1 to WSm to the scan lines 31-1 to 31-m to perform a linear sequential scan of the pixels 20 on a row by row basis.

The power supply scan circuit 50 includes a shift register or other components. The same circuit 50 supplies power supply line potentials DS1 to DS_m to the power supply lines 32-1 to 32-m in synchronism with the linear sequential scan by the write scan circuit 40. The power supply line potentials DS1 to DS_m switch between a first potential V_{ccp} and a second potential V_{ini} which is lower than the first potential V_{ccp}. Here, the second potential V_{ini} is sufficiently lower than an offset voltage V_{ofs} applied by the horizontal drive circuit 60.

The horizontal drive circuit 60 selects either of a signal voltage V_{sig} of the video signal, commensurate with brightness information supplied by a signal supply source (not shown), and the offset voltage V_{ofs} of the video signal as a reference voltage. Then, the same circuit 60 writes the

selected voltage, for example, on a column by column basis, to the pixels 20 of each column of the pixel array section 30 all at once via the signal lines 33-1 to 33-n. That is, the same circuit 60 employs linear sequential driving adapted to write the input signal voltage V_{sig}, on a column by column (line by line) basis, to the pixels of each column all at once.

(Horizontal Drive Circuit)

FIG. 2 is a circuit diagram illustrating an example of specific configuration of an output portion of the horizontal drive circuit 60. Here, FIG. 2 illustrates only the circuit portion in a given row.

The horizontal drive circuit 60 includes at least one pre-charge signal line 61. The same circuit 60 also includes a video signal line 62 and a reference potential line 63. The same circuit 60 further includes horizontal selector switches 64, 65 and 66 which are connected between the lines 61, 62 and 63 and the signal lines 33 (33-1 to 33-n) of the pixel array section 30. Each of the horizontal selector switches 64, 65 and 66 includes, for example, a CMOS switch made up of an NMOS transistor and a PMOS transistor connected in parallel.

And, the horizontal selector switch 64 is controlled to turn on and off by switch control signals PRE and xPRE which are supplied via control lines 67-1 and 67-2. The switch control signals PRE and xPRE are opposite in phase to each other. The horizontal selector switch 65 is controlled to turn on and off by switch control signals SIG and xSIG which are opposite in phase to each other and are supplied via control lines 68-1 and 68-2. The horizontal selector switch 66 is controlled to turn on and off by switch control signals OFS and xOFS which are opposite in phase to each other and are supplied via control lines 69-1 and 69-2.

In the horizontal drive circuit 60 configured as described above, the horizontal selector switch 65 turns on in response to the switch control signals SIG and xSIG which are synchronous with the selection scan by the write scan circuit 40, supplying the signal voltage V_{sig} of the video signal, transmitted by the video signal line 62, to the signal line 33.

The horizontal selector switch 64 turns on in response to the switch control signals PRE and xPRE ahead of the supply of the signal voltage V_{sig} by the horizontal selector switch 65 to the signal line 33, supplying a precharge voltage V_{pre}, transmitted by the precharge signal line 61 and lower than the signal voltage V_{sig}, to the signal line 33 before the signal voltage V_{sig}.

The horizontal selector switch 66 turns on in response to the switch control signals OFS and xOFS during a period of time other than when the horizontal selector switches 64 and 65 are on, supplying an offset voltage V_{ofs}, which is a reference voltage transmitted by the reference potential line 63, to the signal line 33.

As is clear from the above description, the horizontal drive circuit 60 supplies the input signal voltage to the pixels in the row scanned by the write scan circuit 40 via the signal lines 33 (33-1 to 33-n). At the same time, the same circuit 60 increases the voltage level of the input signal voltage in a step-by-step manner (in two steps in the present example). More specifically, the precharge voltage V_{pre}, lower than the signal voltage V_{sig}, is supplied before the signal voltage V_{sig} at a desired voltage level.

It should be noted that the horizontal drive circuit 60 according to the present embodiment increases the signal voltage in two steps, i.e., to the precharge voltage V_{pre} in the first step and to the signal voltage V_{sig} in the second step. However, the present invention is not limited to two steps, but

a plurality of voltage levels may be specified as the precharge voltage V_{pre} so that the same voltage V_{pre} is supplied in a plurality of steps.

(Pixel Circuit)

FIG. 3 is a circuit diagram illustrating a concrete configuration example of the pixel (pixel circuit) 20. As illustrated in FIG. 3, the pixel circuit 20 includes an organic EL element 21 as a light-emitting element. The organic EL element is an example of so-called current-driven light-emitting elements whose emission brightness changes with change in current flowing through the elements. In addition to the organic EL element 21, the pixel circuit 20 includes a drive transistor 22, a write transistor 23, a holding capacitance 24 and an auxiliary capacitance 25.

Here, N-channel TFTs are used as the drive and write transistors 22 and 23. It should be noted, however, that the combination of conduction types of the drive and write transistors 22 and 23 given here is merely exemplary. The combination thereof is not limited to the above.

The organic EL element 21 has its cathode electrode connected to a common power supply line 34 which is shared by all the pixels 20. The drive transistor 22 has its source connected to the anode electrode of the organic EL element 21 and its drain to the power supply line 32 (any of 32-1 to 32-m).

The write transistor 23 has its gate connected to the scan line 31 (any of 31-1 to 31-m), its source to the signal line 33 (any of 33-1 to 33-n) and its drain to the gate of the drive transistor 22. The holding capacitance 24 has one of its ends connected to the gate of the drive transistor 22 and the other end to the source of the drive transistor 22 (anode electrode of the organic EL element 21).

The auxiliary capacitance 25 has one of its ends connected to the source of the drive transistor 22 and the other end to the cathode electrode of the organic EL element 21 (common power supply line 34). The auxiliary capacitance 25 is connected in parallel with the organic EL element 21, thus compensating for the lack of capacitance of the organic EL element 21. That is, the same capacitance 25 is not an absolutely necessary component, but instead may be omitted if the organic EL element 21 has sufficient capacitance.

In the pixel 20 configured as described above, the write transistor 23 conducts in response to the scan signal WS applied to its gate by the write scan circuit 40 via the scan line 31. As a result, the write transistor 23 samples either of the input signal voltage V_{sig} of the video signal, commensurate with brightness information, and the offset voltage V_{ofs} of the video signal supplied by the horizontal drive circuit 60 via the signal line 33 and writes the selected voltage to the pixel 20. The written voltage, which is either the input signal voltage V_{sig} or the offset voltage V_{ofs} , is held by the holding capacitance 24.

The drive transistor 22 is supplied with a current from the power supply line 32 (any of 32-1 to 32-m) when the potential DS of the same line 32 is at the first potential V_{ccp} . As a result, the drive transistor 22 supplies a drive current, commensurate with the input signal voltage V_{sig} held in the holding capacitance 24, to the organic EL element 21, thus driving the same element 21 with a current.

(Pixel Structure)

FIG. 4 illustrates an example of sectional structure of the pixel 20. As illustrated in FIG. 4, the pixel or pixel circuit 20 includes pixel circuits such as the drive and write transistors 22 and 23 formed on a glass substrate 201. On top of the pixel circuit, an insulating film 202 and a window insulating film 203 are formed. The organic EL element 21 is provided in a recessed portion 203A of the window insulating film 203.

The organic EL element 21 includes an anode electrode 204, an organic layer (electron transport layer, light-emitting layer, hole transport/injection layer) 205 formed on the anode electrode 204 and a cathode electrode 206 formed on the organic layer 205 for all the pixels. The anode electrode 204 includes, for example, a metal formed on the bottom of the recessed portion 203A of the window insulating film 203. The cathode electrode 206 includes, for example, a transparent electroconductive film.

In the organic EL element 21, the organic layer 205 is formed by successively depositing a hole transport/injection layer 2051, a light-emitting layer 2052, an electron transport layer 2053 and an electron injection layer (not shown) on top of the anode electrode 204. As the organic EL element 21 is driven with a current by the drive transistor 22 illustrated in FIG. 2, a current flows from the drive transistor 22 to the organic layer 205 via the anode electrode 204. This causes electrons and holes to recombine in the light-emitting layer 2052 of the organic layer 205, thus allowing the organic EL element 21 to emit light.

As illustrated in FIG. 4, after the organic EL element 21 is formed for each pixel on the glass substrate 201 via the insulating film 202 and the window insulating film 203, a sealing substrate 208 is bonded to the organic EL element 21 via a passivation film 207 with an adhesive 209. A display panel 70 is formed as the organic EL element 21 is sealed by the sealing substrate 208.

(Threshold Correction Function)

Here, the power supply scan circuit 50 switches the potential DS of the power supply line 32 between the first and second potentials V_{ccp} and V_{ini} after the write transistor 23 conducts while the horizontal drive circuit 60 supplies the offset voltage V_{ofs} to the signal line 33 (any of 33-1 to 33-n). This switching of the potential DS of the power supply line 32 ensures that a voltage corresponding to the threshold voltage V_{th} of the drive transistor 22 is held by the holding capacitance 24.

The voltage corresponding to the threshold voltage V_{th} of the drive transistor 22 is held by the holding capacitance 24 for the following reason. That is, the characteristics of the drive transistor 22 such as the threshold voltage V_{th} and the mobility μ may change between different pixels due, for example, to a manufacturing process variation or secular change. Such a change leads to a change in the drain-to-source current (drive current) I_{ds} between different pixels even if the same potential is applied to the gates of all the drive transistors 22. This results in a variation of the emission brightness. The holding capacitance 24 holds the voltage corresponding to the threshold voltage V_{th} to cancel (correct) the impact of variation of the threshold voltage V_{th} between different pixels.

The threshold voltage V_{th} of the drive transistor 22 is corrected in the following manner. That is, the holding capacitance 24 holds the threshold voltage V_{th} in advance. As a result, when the drive transistor 22 is driven by the input signal voltage V_{sig} , the threshold voltage V_{th} of the drive transistor 22 is canceled by the voltage corresponding to the threshold voltage V_{th} held by the holding capacitance 24. In other words, the threshold voltage V_{th} is corrected.

The threshold correction function works as described above. This function maintains the emission brightness of the organic EL element 21 unchanged even in the event of a variation of the threshold voltage V_{th} between different pixels or secular change without being affected by such a change or deterioration. The principle of the threshold correction function will be described in detail later.

(Mobility Correction Function)

The pixel **20** illustrated in FIG. 3 has not only the aforementioned threshold correction function but also the mobility correction function. That is, the mobility is corrected to cancel the dependence of the drain-to-source current I_{ds} of the drive transistor **22** on the mobility μ during a mobility correction period when the holding capacitance **24** holds the input signal voltage V_{sig} . The mobility correction period is a period of time during which the horizontal drive circuit **60** supplies the signal voltage V_{sig} of the video signal to the signal line **33** (any of **33-1** to **33-n**) and during which the write transistor **23** conducts in response to the scan signal WS (any of WS_1 to WS_m) from the write scan circuit **40**. The detailed principle and operation of the mobility correction will be described later.

(Bootstrap Function)

The pixel **20** illustrated in FIG. 3 further has the bootstrap function. That is, the horizontal drive circuit **60** stops supplying the scan signal WS (any of WS_1 to WS_m) to the scan line **31** (any of **31-1** to **31-m**) when the holding capacitance **24** holds the input signal voltage V_{sig} . This causes the write transistor **23** to stop conducting, electrically separating the gate of the drive transistor **22** from the signal line **33** (any of **33-1** to **33-n**). As a result, a gate potential V_g of the drive transistor **22** changes with change in a source potential V_s thereof. This maintains the gate-to-source voltage V_{gs} of the drive transistor **22** constant.

(Circuit Operation)

Next, a description will be given below about the circuit operation of the organic EL display apparatus **10** according to the present embodiment based on the timing diagram shown in FIG. 5 and with reference to the explanatory diagrams shown in FIGS. 6 and 7. It should be noted that the write transistor **23** is represented by a switch symbol in FIGS. 6 and 7 for simplification of the drawings. It should also be noted that the organic EL element **21** has a parasitic capacitance and that the parasitic capacitance and auxiliary capacitance **25** are represented by a combined capacitance C_{sub} .

The timing diagram of FIG. 5 shows, on a common time axis, the changes of the potential (scan signal) WS of the scan line **31** (any of **31-1** to **31-m**), the potential DS of the power supply line **32** (any of **32-1** to **32-m**), the potential ($V_{pre}/V_{sig}/V_{ofs}$) of the signal line **33** (any of **33-1** to **33-n**), the switch control signals (PRE, SIG and OFS), and the gate and source potentials V_g and V_s of the drive transistor **22** for a period of $1H$ (H represents the horizontal scan period).

<Emission Period>

In the timing diagram of FIG. 5, the organic EL element **21** emits light before time **t1** (emission period). During this emission period, the potential DS of the power supply line **32** is at the high potential V_{ccp} (first potential). As illustrated in FIG. 6(A), the drive current (drain-to-source current) I_{ds} is supplied to the organic EL element **21** from the power supply line **32** via the drive transistor **22**. As a result, the organic EL element **21** emits light at the brightness commensurate with the drive current I_{ds} .

<Preparation Period for Threshold Correction>

At time **t1**, the linear sequential scan of a new field begins. When the potential DS of the power supply line **32** changes from the high potential V_{ccp} to the low potential V_{ini} (second potential) which is sufficiently lower than the offset voltage V_{ofs} of the signal line **33**, the source potential V_s of the drive transistor **22** also begins to drop to the low potential V_{ini} .

Next, the write scan circuit **40** outputs the scan signal WS at time **t2**, changing the potential WS of the scan line **31** to the high potential. As a result, the write transistor **23** starts conducting as illustrated in FIG. 6(C). At this time, the horizontal

drive circuit **60** supplies the offset voltage V_{ofs} to the signal line **33**. As a result, the gate potential V_g of the drive transistor **22** becomes equal to the offset voltage V_{ofs} . On the other hand, the source potential V_s of the drive transistor **22** is at the low potential V_{ini} which is sufficiently lower than the offset voltage V_{ofs} .

Here, the low potential V_{ini} is set so that the gate-to-source voltage V_{gs} of the drive transistor **22** is greater than the threshold voltage V_{th} of the same transistor **22**. As described above, preparations for threshold voltage correction are complete when the gate and source potentials V_g and V_s of the drive transistor **22** are initialized respectively to the offset voltage V_{ofs} and the low potential V_{ini} .

<Threshold Correction Period>

Next, when the potential DS of the power supply line **32** changes from the low potential V_{ini} to the high potential V_{ccp} at time **t3** as illustrated in FIG. 6D, the source potential V_s of the drive transistor **22** begins to increase. The gate-to-source voltage V_{gs} of the drive transistor **22** will soon become equal to the threshold voltage V_{th} of the same transistor **22**, causing the voltage corresponding to the threshold voltage V_{th} to be written to the holding capacitance **24**.

Here, the period of time during which the voltage corresponding to the threshold voltage V_{th} is written to the holding capacitance **24** is referred to as a threshold correction period for reasons of convenience. It should be noted that, during the threshold correction period, a potential V_{cath} of the common power supply line **34** is set so as to bring the organic EL element **21** into a cutoff state. This is intended to ensure that all the current flows into the holding capacitance **24**, and none into the organic EL element **21**.

Next, the potential WS of the scan line **31** changes to the low potential at time **t4**. As a result, the write transistor **23** stops conducting. At this time, the gate of the drive transistor **22** is placed into a floating state. However, the gate-to-source voltage V_{gs} is equal to the threshold voltage V_{th} of the drive transistor **22**. As a result, the drive transistor **22** is in a cutoff state. Therefore, the drain-to-source current I_{ds} does not flow.

<Precharge Period>

At time **t5** after the end of the threshold correction period, the switch control signal OFS is deactivated (low potential). Next, at time **t6**, the switch control signal PRE is activated, turning on the horizontal selector switch **64**. As a result, the horizontal drive circuit **60** supplies the precharge voltage V_{pre} to the signal line **33**, as illustrated in FIG. 7(A). This changes the potential of the signal line **33** from the offset voltage V_{ofs} to the precharge voltage V_{pre} .

Next, at time **t7**, the scan signal WS is activated. That is, the potential WS of the scan line **31** changes to the high potential, bringing the write transistor **23** into conduction as illustrated in FIG. 7(B). This causes a precharge to be performed which samples and writes the precharge voltage V_{pre} in advance so as to apply the same voltage V_{pre} to the gate of the drive transistor **22**. And, as the gate potential V_g of the drive transistor **22** becomes equal to the precharge voltage V_{pre} , the source potential V_s of the same transistor **22** begins to rise.

<Write Period/Mobility Correction Period>

Next, at time **t8**, the switch control signal PRE is deactivated, turning off the horizontal selector switch **64**. Then, at time **t9**, the switch control signal SIG is activated, turning on the horizontal selector switch **65**. As a result, the horizontal drive circuit **60** supplies the signal voltage V_{sig} of the video signal to the signal line **33**, as illustrated in FIG. 7(C). This changes the potential of the signal line **33** from the precharge voltage V_{pre} to the signal voltage V_{sig} .

And, the signal voltage V_{sig} is applied to the gate of the drive transistor **22** via the write transistor **23** which is con-

11

ducting. The gate potential V_g of the drive transistor **22** becomes equal to the signal voltage V_{sig} . At this time, the organic EL element **21** is initially in a cutoff state (high impedance state). Therefore, the drain-to-source current Ids of the drive transistor **22** flows into the combined capacitance C_{sub} connected in parallel with the organic EL element **21**, thus starting the charging of the combined capacitance C_{sub} .

As the combined capacitance C_{sub} is charged, the source potential V_s of the drive transistor **22** begins to increase. The gate-to-source voltage V_{gs} of the drive transistor **22** will soon become equal to $V_{sig} + V_{th} - \Delta V$. That is, an increment ΔV of the source potential V_s is subtracted from the voltage ($V_{sig} + V_{th}$) held by the holding capacitance **24**. In other words, the increment ΔV acts so as to discharge the charge held by the holding capacitance **24**. This means that negative feedback is applied. Hence, the increment ΔV of the source potential V_s is a feedback amount of the negative feedback.

As described above, the drain-to-source current Ids flowing through the drive transistor **22** is negative fed back to the gate input of the same transistor **22**, namely, to the gate-to-source voltage V_{gs} . This cancels the dependence of the drain-to-source current Ids of the drive transistor **22** on the mobility μ . That is, the mobility correction is performed to correct the variation of the mobility μ between different pixels.

More specifically, the higher the signal voltage V_{sig} of the video signal, the larger the drain-to-source current Ids , and therefore, the larger the absolute value of the feedback amount (correction amount) ΔV of the negative feedback. This allows for mobility correction according to the emission brightness level. Further, if we assume that the signal voltage V_{sig} of the video signal is constant, the larger the mobility μ of the drive transistor **22**, the larger the absolute value of the feedback amount ΔV of the negative feedback. This eliminates the variation of the mobility μ between different pixels.

<Emission Period>

Next, the potential WS of the scan line **31** changes to the low potential at time $t7$ (or, the switch control signal SIG is deactivated at the same time or later). As a result, the write transistor **23** stops conducting (turns off) as illustrated in FIG. 7(D). As a result, the gate of the drive transistor **22** is disconnected from the signal line **33**. At the same time, the drain-to-source current Ids begins to flow into the organic EL element **21**. As a result, the anode potential of the same element **21** increases with increase in the drain-to-source current Ids .

This increase in the anode potential of the organic EL element **21** is none other than the increase in the source potential V_s of the drive transistor **22**. If the source potential V_s of the drive transistor **22** increases, the gate potential V_g of the same transistor **22** increases as well due to the bootstrap operation of the holding capacitance **24**. At this time, the increment of the gate potential V_g is equal to the increment of the source potential V_s . Hence, the gate-to-source voltage V_{gs} of the drive transistor **22** is maintained constant at $V_{sig} + V_{th} - LV$ during the emission period.

Then, at time $t11$, the switch control signal OFS is activated, turning on the horizontal selector switch **66**. As a result, the horizontal drive circuit **60** supplies the offset voltage V_{ofs} to the signal line **33**. This changes the potential of the signal line **33** from the signal voltage V_{sig} of the video signal to the offset voltage V_{ofs} .

(Principle of the Threshold Correction)

Here, a description will be given below about the principle of the threshold correction of the drive transistor **22**. The drive transistor **22** operates as a constant current source as it is designed to operate in the saturated region. This allows the drive transistor **22** to supply a constant level of the drain-to-

12

source current (drive current) Ids , given by the following equation (1), to the organic EL element **21**.

$$Ids = (1/2) \cdot \mu \cdot (W/L) \cdot Cox \cdot (V_{gs} - V_{th})^2 \quad (1)$$

where W is the channel width of the drive transistor **22**, L the channel length and Cox the gate capacitance per unit area.

FIG. 8 illustrates the characteristic of the drain-to-source current Ids vs the gate-to-source voltage V_{gs} of the drive transistor **22**. As illustrated in this characteristic chart, without the correction of the variation of the threshold voltage V_{th} of the drive transistor **22**, when the threshold voltage V_{th} is V_{th1} , the drain-to-source current Ids associated with the gate-to-source voltage V_{gs} is $Ids1$. On the other hand, when the threshold voltage V_{th} is V_{th2} ($V_{th2} > V_{th1}$), the drain-to-source current Ids associated with the same gate-to-source voltage V_{gs} is $Ids2$ ($Ids2 < Ids1$). That is, if the threshold voltage V_{th} of the drive transistor **22** changes, the drain-to-source current Ids changes as well even when the gate-to-source voltage V_{gs} remains constant.

In the case of the pixel (pixel circuit) **20** configured as described above, on the other hand, the gate-to-source voltage V_{gs} of the drive transistor **22** at the time of emission is $V_{sig} + V_{th} - \Delta V$ as mentioned earlier. By substituting this into Equation (1), the drain-to-source current Ids can be expressed by the following equation:

$$Ids = (1/2) \cdot \mu \cdot (W/L) \cdot Cox \cdot (V_{sig} - \Delta V)^2 \quad (2)$$

That is, the term of the threshold voltage V_{th} of the drive transistor **22** is cancelled. Therefore, the drain-to-source current Ids supplied from the drive transistor **22** to the organic EL element **21** is not dependent upon the threshold voltage V_{th} of the drive transistor **22**. As a result, the drain-to-source current Ids remains unchanged even in the event of a change in the threshold voltage V_{th} between different pixels due to a manufacturing process variation or secular change. Hence, the emission brightness of the organic EL element **21** also remains unchanged.

(Principle of the Mobility Correction)

Next, a description will be given below about the principle of the mobility correction of the drive transistor **22**. FIG. 9 illustrates characteristic curves comparing two pixels. One of the curves represents a pixel A whose drive transistor **22** has a relatively large level of the mobility μ . The other curve represents a pixel B whose drive transistor **22** has a relatively small level of the mobility μ . If the drive transistor **22** is, for example, a polysilicon thin film transistor, the mobility μ inevitably varies between different pixels.

For example, in the case that the same level of the input signal voltage V_{sig} is written to both the pixels A and B when the mobility μ is different between the two pixels, if any correction is not performed on the mobility μ , there will be a large difference between a drain-to-source current $Ids1'$ flowing into the pixel A with the larger mobility μ and a drain-to-source current $Ids2'$ flowing into the pixel B with the smaller mobility μ . Thus, a large difference in the drain-to-source current Ids between pixels due to a variation of the mobility μ will impair the uniformity over the screen.

As is clear from Equation (1) relating to the transistor characteristic, the larger the mobility μ , the larger the drain-to-source current Ids . Therefore, the larger the mobility μ , the larger the feedback amount ΔV of the negative feedback. As illustrated in FIG. 8, a feedback amount $AV1$ of the pixel A with the larger mobility μ is greater than a feedback amount $AV2$ of the pixel B with the smaller mobility μ . For this reason, the mobility correction negative feeds back the drain-to-source current Ids of the drive transistor **22** to the input signal voltage V_{sig} . As a result, the larger the mobility μ , the

more the drain-to-source current Ids is negative fed back. This suppresses the variation of the mobility μ .

More specifically, if the pixel A with the larger mobility μ is corrected using the feedback amount $\Delta V1$, the drain-to-source current Ids drops significantly from $Ids1'$ to $Ids1$. On the other hand, the feedback amount $\Delta V2$ of the pixel B with the smaller mobility μ is small. Therefore, the drain-to-source current Ids drops only from $Ids2'$ to $Ids2$, which is not a significant decline. As a result, the drain-to-source current $Ids1$ of the pixel A becomes approximately equal to the drain-to-source current $Ids2$ of the pixel B, thus correcting the variation of the mobility μ .

Summing up the above, if the pixels A and B have different values of the mobility μ , the feedback amount $\Delta V1$ of the pixel A with the larger mobility μ is larger than the feedback amount $\Delta V2$ of the pixel B with the smaller mobility μ . That is, the larger the mobility μ of the pixel, the larger the feedback amount ΔV , and the more the drain-to-source current Ids decreases. That is, the drain-to-source current Ids of the drive transistor **22** is negative fed back to the input signal voltage $Vsig$. This provides different pixels having different levels of the mobility μ with a uniform level of the drain-to-source current Ids , thus allowing the variation of the mobility μ to be corrected.

Here, a description will be given below about the relationship between the signal potential (sampled potential) $Vsig$ of the video signal and the drain-to-source current Ids of the drive transistor **22** in the pixel (pixel circuit) **20** illustrated in FIG. 3. The relationship will be described comparing the cases with and without the threshold and mobility corrections with reference to FIG. 10.

In FIG. 10, (A) illustrates the case without the threshold or mobility correction. (B) illustrates the case with the threshold correction but without the mobility correction. (C) illustrates the case with both the threshold and mobility corrections. As illustrated in FIG. 10(A), if neither of the threshold and mobility corrections is performed, there is a large difference in the drain-to-source current Ids between the pixels A and B because of the variations in the threshold voltage Vth and the mobility μ between the two pixels.

In contrast, if only the threshold correction is performed, the variation of the drain-to-source current Ids can be reduced to a certain extent by this threshold correction as illustrated in FIG. 10(B). However, there is still a difference in the drain-to-source current Ids between the pixels A and B attributable to the variation of the mobility μ between the two pixels. When both the threshold and mobility corrections are performed, it is possible to almost completely eliminate the difference in the drain-to-source current Ids between the pixels A and B attributable to the variations of the threshold voltage Vth and the mobility μ between the two pixels as shown in FIG. 10(C). As a result, the brightness of the organic EL element **21** remains unchanged for all shades, thus providing excellent on-screen image.

(Operation and Effect of the Present Embodiment)

In the organic EL display apparatus **10** according to the present embodiment described above, there is a relationship between the optimal mobility correction time for the mobility correction to provide the best image quality and the gate-to-source voltage Vgs of the drive transistor **22** at the beginning of the correction. That is, the higher the gate-to-source voltage Vgs , the shorter the optimal mobility correction time. In other words, the lower the gate-to-source voltage Vgs , the longer the optimal mobility correction time.

In consideration of the relationship between the optimal mobility correction time and gate-to-source voltage Vgs at the beginning of the correction, the organic EL display appa-

ratus **10** according to the present embodiment is characterized in that, prior to increasing the level of the input signal voltage (voltage of the signal line **33**) to be sampled in a step-by-step manner and writing the signal voltage $Vsig$ at a desired voltage level, the same apparatus **10** performs a precharge adapted to write the precharge voltage $Vpre$, lower than the signal voltage $Vsig$, so as to apply the same voltage $Vpre$ to the gate of the drive transistor **22** in advance.

As described above, performing a precharge with the precharge voltage $Vpre$ ahead of the writing of the signal voltage $Vsig$ causes the gate potential Vg of the drive transistor **22** to increase to the precharge voltage $Vpre$. The source potential Vs will also increase with increase in the gate potential Vg . The increase in the source potential Vs keeps the gate-to-source voltage Vgs of the drive transistor **22** at the time of writing of the signal voltage $Vsig$, i.e., at the beginning of the mobility correction period, lower (smaller) than if the precharge were not performed.

And, as the gate-to-source voltage Vgs of the drive transistor **22** at the beginning of the mobility correction period becomes smaller, the optimal mobility correction time will be longer. That is, the mobility correction time can be extended longer than if the precharge were not performed. The longer optimal mobility correction time ensures a relatively smaller variation in the mobility correction time, thus suppressing the variation in brightness attributable to the variation in the mobility correction time.

Further, the longer optimal mobility correction time permits the width (period from time $t9$ to $t10$ in FIG. 5) of the scan signal **WS**, serving as a write pulse, to be set to the optimal width even if a system configuration in which the mobility correction time is determined by a unit of master clock pulse width serving as a reference of system operation is adapted.

It should be noted that, in the aforementioned embodiment, a case has been described as an example where the embodiment is applied to the organic EL display apparatus using the organic EL elements as light-emitting elements of the pixels (pixel circuits) **20**. However, the present invention is not limited thereto but is applicable to display apparatuses in general using current-driven light-emitting elements (light-emitting elements) whose emission brightness changes with change in current flowing through the elements.

APPLICATION EXAMPLES

The aforementioned display apparatus according to the present invention is applicable to display apparatuses of electronic equipment used in all fields which is designed to display the image or video of the video signal input to or generated therein. Among such electronic equipment are a wide variety of different equipment illustrated in FIGS. 11 to 15, namely, a digital camera, laptop personal computer, mobile terminal device such as mobile phone, and video camcorder.

A description will be given below about examples of electronic equipment to which the present invention is applied.

It should be noted that among the display apparatuses according to the present invention are those in a modular form having a sealed configuration. A display apparatus which fits into this category is a display module formed by attaching a transparent opposed section made of glass or other material to the pixel array section **30**. This transparent opposed section may have a color filter, protective film or even a light-shielding film. It should be noted that the display module may have a circuit section, FPC (flexible printed circuit) or other circuitry provided for exchange of signals between the pixel array section and external equipment.

15

FIG. 11 is a perspective view illustrating a television set to which the present invention is applied. The television set according to the present application example includes a video display screen section 101 which includes a front panel 102, a filter glass 103 and other components. This television set is manufactured by using the display apparatus according to the present invention as the video display screen section 101.

FIG. 12 shows perspective views illustrating a digital camera to which the present invention is applied. (A) is a perspective view as seen from the front of the camera. (B) is a perspective view as seen from the rear thereof. The digital camera according to the present application example includes a flash light-emitting section 111, a display section 112, a menu switch 113, a shutter button 114 and other components. This digital camera is manufactured by using the display apparatus according to the present invention as the display section 112.

FIG. 13 is a perspective view illustrating a laptop personal computer to which the present invention is applied. The laptop personal computer according to the present application example includes a main body 121, a keyboard 122 adapted to be operated to enter information such as characters, a display section 123 adapted to display images and other components. This laptop personal computer is manufactured by using the display apparatus according to the present invention as the display section 123.

FIG. 14 is a perspective view illustrating a video camcorder to which the present invention is applied. The video camcorder according to the present application example includes a main body section 131, a front-facing lens 132 adapted to capture the subject image, a start/stop switch 133 for image capture, a display section 134 and other components. This video camcorder is manufactured by using the display apparatus according to the present invention as the display section 134.

FIG. 15 shows perspective views illustrating a mobile terminal device such as mobile phone to which the present invention is applied. (A) is a front view of the mobile phone as opened. (B) is a side view thereof. (C) is a front view of the mobile phone as closed. (D) is a left side view. (E) is a right side view. (F) is a top view. (G) is a bottom view. The mobile phone according to the present application example includes an upper enclosure 141, a lower enclosure 142, a connecting section (hinge section in this case) 143, a display 144, a subdisplay 145, a picture light 146, a camera 147 and other components. This mobile phone is manufactured by using the display apparatus according to the present invention as the display 144 and the subdisplay 145.

The present invention extends the optimal mobility correction time, thus ensuring a relatively smaller variation in the mobility correction time. This suppresses the variation in brightness attributable to the variation in the mobility correction time and also permits the write pulse to be set to the optimal pulse width.

The invention claimed is:

1. A display apparatus comprising:

a pixel array section including a plurality of pixels, at least one of the plurality of pixels having a light-emitting element, a write transistor configured to write an input signal voltage from a signal line to a holding capacitance during a write period, and a drive transistor configured to drive the light-emitting element based on the input signal voltage held by the holding capacitance;
a drive circuit configured to supply the input signal voltage via the signal lines to the plurality of pixels, wherein within a horizontal scanning period, a potential of the signal line is iteratively increased from an offset voltage,

16

to a pre-charge voltage between the offset voltage and the input signal voltage, and then to the input signal voltage, an increase to the pre-charge voltage occurring before the write transistor is turned on to write the input signal voltage, and

at least one of the plurality of pixels performs a correction by negatively feeding back the drain-to-source current of the drive transistor to a gate of the drive transistor during the write period.

2. The display apparatus according to claim 1, wherein after the correction, the potential of the signal line is returned to the offset voltage.

3. The display apparatus according to claim 1, wherein the pixel array section is sequentially scanned on a row-by-row basis, and the signal line corresponds to a given row of pixels, such that within the horizontal scanning period, the potential of the signal line is iteratively increased from the offset voltage, to the pre-charge voltage, and then to the input signal voltage for the given row of pixels.

4. A driving method of a display apparatus, the display apparatus comprising a pixel array section including a plurality of pixels, at least one of the plurality of pixels having a light-emitting element, a write transistor configured to write an input signal voltage from a signal line to a holding capacitance during a write period, and a drive transistor configured to drive the light-emitting element based on the input signal voltage held by the holding capacitance, and a write scan circuit the driving method comprising:

providing the input signal voltage via the signal line to the plurality of pixels, and

performing a correction by negatively feeding back the drain-to-source current of the drive transistor to a gate of the drive transistor during the write period, wherein

within a horizontal scanning period, a potential of the signal line is iteratively increased from an offset voltage, to a pre-charge voltage between the offset voltage and the input signal voltage, and then to the input signal voltage, an increase to the pre-charge voltage occurring before the write transistor is turned on to write the input signal voltage.

5. The driving method according to claim 4, wherein after the correction, the potential of the signal line is returned to the offset voltage.

6. The driving method according to claim 4, wherein the pixel array section is sequentially scanned on a row-by-row basis, and the signal line corresponds to a given row of pixels, such that within the horizontal scanning period, the potential of the signal line is iteratively increased from the offset voltage, to the pre-charge voltage, and then to the input signal voltage for the given row of pixels.

7. An electronic equipment having a display apparatus, the display apparatus comprising:

a pixel array section including a plurality of pixels, at least one of the plurality of pixels having a light-emitting element, a write transistor configured to write an input signal voltage from a signal line to a holding capacitance during a write period, and a drive transistor configured to drive the light-emitting element based on the input signal voltage held by the holding capacitance;

a drive circuit configured to supply the input signal voltage via the signal line to the plurality of pixels, wherein within a horizontal scanning period, a potential of the signal line is iteratively increased from an offset voltage, to a pre-charge voltage between the offset voltage and the input signal voltage, and then to the input signal

17

voltage, an increase to the pre-charge voltage occurring before the write transistor is turned on to write the input signal voltage, and at least one of the plurality of pixels performs a correction by negatively feeding back the drain-to-source current of the drive transistor to a gate of the drive transistor during the write period.

8. The electronic equipment according to claim 7, wherein after the correction, the potential of the signal line is returned to the offset voltage.

9. The electronic equipment according to claim 7, wherein the pixel array section is sequentially scanned on a row-by-row basis, and the signal line corresponds to a given row of pixels, such that within the horizontal scanning period, the potential of the signal line is iteratively increased from the offset voltage, to the pre-charge voltage, and then to the input signal voltage for the given row of pixels.
